UNITED STATES PATENT OFFICE.

WILLIAM H. PEAK, OF JONESBORO, ILLINOIS.

COPY-HOLDER.

SPECIFICATION forming part of Letters Patent No. 736,005, dated August 11, 1903.

Application filed March 26, 1903. Serial No. 149,746. (No model.)

To all whom it may concern:

Be it known that I, WILLIAM H. PEAK, a citizen of the United States, residing at Jonesboro, in the county of Union, State of Illinois, have invented certain new and useful Improvements in Copy-Holders, of which the following is a specification, reference being had therein to the accompanying drawings.

This invention relates to a copy-holder, and particularly to the structure adapted for use in connection with type-writing machines.

The invention has for an object to improve the construction and arrangement of the paper-guide and friction-roller coöperating with the paper-carrying cylinder.

A further object of the invention is to improve the supporting means for the holder, so that it may be adjusted in any desired position most convenient to the operator.

Other and further objects and advantages of the invention will be hereinafter set forth and the novel features thereof defined by the appended claims.

In the drawings, Figure 1 is an elevation of the copy-holder mounted upon a support by which an adjustment in the vertical and horizontal plane may be secured. Fig. 2 is a central vertical section through the copy-holder. Fig. 3 is a perspective of a modified application of the invention, and Fig. 4 is a plan of the base-plate.

Like letters of reference refer to like parts in the several figures of the drawings.

The letter A designates a frame having vertical standards A' at its opposite ends and mounted upon a base-plate A² in any desired manner. The feed roller or cylinder B is pivotally mounted in these standards by means of a shaft B', which is provided with a handle

B² for the purpose of rotating the feed-roller. Beneath this roller a paper-guide C is pivotally mounted in the standards A', as shown at C', and extends beneath the lower segment of the roller B. The front portion of this guide

is bent inward, as shown at C², to closely approach the roller and may be suitably ruled or graduated, as shown. This guide is also provided with a recessed portion C³, within which the friction-roller C⁴ is pivotally mounted.

This friction-roller is normally held in contact with the feed-roller by means of a

spring C⁵, disposed between the frame A and the upper surface of the guide C at one side of the pivot thereof, so as to hold the roller C⁴ in proper frictional contact with the feed-roller. These rollers may be of any desired material, preferably having rubber or elastic surfaces, such as ordinarily used in typewriters. Upon the front of the guide C fingers C⁶ are suitably secured and extend upward over the feed-roller B, so as to guide the paper backward from the front of the roller.

In Fig. 1 a desirable form of support is shown adapted for application to either a desk, table, or base of a type-writer and comprises a clamp D, having a sleeve D', within which a vertical standard D² is adjustably secured by means of a set-screw D³ and provided at its upper end with a socket D⁴, adapted to receive one end D⁵ of the N-shaped connector D⁶, which may be secured against vertical movement in said socket by means of a set-screw D⁷, and in order to prevent a rotary movement in the socket interlocking teeth D⁸ are provided. At the opposite end of the connector D⁶ a similar socket E is provided, in which a depending rod E' from a support E beneath the base-plate A² is adapted to enter and to be secured against vertical movement therein by means of a set-screw E², while teeth E³ are provided upon the rod and socket to hold the same against rotary movement. This support for the copy-holder permits a vertical adjustment and also a rotary adjustment in a horizontal plane, so that the holder may be brought into the most convenient position for use of the operator, either at the back of the type-writing machine or at one side thereof, as may be found most desirable.

As showing one desirable means for connecting the frame A and the base-plate A² the said plate has been illustrated as provided with lugs or ears A³ upon the opposite side edges thereof adapted to engage corresponding recesses in the edges of the frame A. The plate A² is also provided with a latch A⁶, pivoted to the under face thereof at A⁷ and adapted to swing through a cut-away portion A⁸ in one of the standards A' and into contact with the upper face of the frame A to hold the parts in engagement with each other.

In Fig. 3 a modified application of the

holder is shown in which the base-plate A² is provided at each end with depending arms A⁴ and clips A⁵, adapted to engage any desired part of a type-writing machine, as indicated by dotted lines. This application is particularly adapted for book type-writers, such as the Elliott-Hatch type-writing machine.

From the foregoing description the operation of the several parts will be clearly apparent, and it will be obvious that changes may be made in the details of construction and configuration without departing from the spirit of the invention as defined by the appended claims.

Having described my invention and set forth its merits, what I claim, and desire to secure by Letters Patent, is—

1. In a copy-holder, a feed-roller, a paper-guide pivotally mounted beneath said roller, and a spring for holding one edge of said guide adjacent to said roller.

2. In a copy-holder, a feed-roller, a paper-guide pivotally mounted beneath the same, a friction-roller pivoted in said guide, and a spring beneath said guide for holding the friction-roller in contact with the feed-roller.

3. In a copy-holder, a feed-roller, a paper-guide pivotally mounted beneath the same at one side of the pivot of said roller, a friction-roller pivoted in said guide, a spring beneath said guide for holding the friction-roller in

contact with the feed-roller, and guide-fingers extending upward from said paper-guide.

4. In a copy-holder, a feed-roller, a paper-guide surrounding a portion thereof, a base-plate having a depending pivot at one end, a vertical standard for supporting said plate, a connecting-bar between said standard and plate having at opposite ends a pivot and socket connected by a diagonally-disposed portion, and means to permit an adjustment at each end thereof.

5. In a copy-holder, a frame, a feed-roller mounted therein, a base-plate provided with lugs upon opposite side edges thereof, and a latch pivoted upon said plate to engage said frame.

6. In a copy-holder, a frame having standards at opposite ends, a feed-roller mounted in said standards, a base-plate provided with lugs at opposite sides thereof, and a latch-hook pivoted to the under face of said plate to swing through a cut-away portion of one standard into engagement with the upper face of said frame.

In testimony whereof I affix my signature in presence of two witnesses.

WILLIAM H. PEAK.
